METHOD OF SUPPORTING WRAPPED
MEAT CUTS

Gordon E. Gott, Cambridge, Mass., assignor to
Dewey and Almy Chemical Company, North
Cambridge, Mass., a corporation of Massa-
chusetts

Application December 30, 1938, Serial No. 248,589

7 Claims. (Cl. 99—174)

This invention relates to the method of handling large cuts of beef which are to be preserved and stored in moisture-proof and air-tight bags and is particularly directed to the handling of beef sides and quarters, although it may be used for the handling of carcasses of smaller animals.

According to methods which are already known, large beef cuts may be protected from all deleterious action during refrigeration or may be made ready for quick freezing by enclosing the cut in a flexible and distensible bag, sealing the bag hermetically, and exhausting the air in the intervening space between the bag and the carcass.

The best practice for the shipment of chilled beef is to hang each side or quarter individually on hooks suspended from trolleys or a rail so that all portions of the cut are freely exposed to the cold atmosphere. However, in attempts to follow this well established practice when wrapped and vacuumized beef is to be handled, considerable difficulty has hitherto been experienced in supporting the beef cut properly and in sealing off the bag in an air-tight manner.

The prior practice has always contemplated the tying down of the neck of the bag against the shank of the suspending hook, and strains of handling have broken the seal.

The present invention has for its objects to provide a process by which cuts may be expeditiously handled, to allow the bags to be sealed off in a dependable manner, to prevent the hooks from tearing the bag, and to provide a method by which cuts may be handled on conventional hooks and on conventional trolley systems, both in the packing plant and in refrigerating cars and ships without the need of any special apparatus. These and other objects of the invention will become apparent from the specification and from the annexed drawing in which

Figure 1 represents a perspective view of the unexpanded bag suitable for enclosing the beef quarter as modified in accordance with this invention;

Figure 2 illustrates the beef quarter in perspective after being inserted in the bag and shows the bag and the expansion container in vertical section;

Figure 3 illustrates a later step in the process, and

Figure 4 shows a beef quarter packaged in accordance with this invention and suspended from the conventional hook and trolley.

In carrying out my invention, I provide a finger or protuberance 4 as an integral part of the bag

2. Although other materials may be used for the purpose, the most satisfactory material for forming the bag, so far known to me, is the dried deposit of *Hevea latex* modified by the addition of approximately 8% of wax. For convenience in description and without restricting myself to any particular composition or material, I shall refer to such bags as "rubber" bags. Also, according to known methods, the rubber bag, which initially possesses much smaller dimensions than those of a beef quarter, is snapped over the open end of a container 5 and air, which is trapped between the bag and the container is exhausted through a suitable vacuum connection. The bag then expands to the full size of the casing 5 and in this expanded condition is amply large to enclose the quarter or side of beef.

The beef quarter, 6, is suspended from a conventional hook 8, which in turn is hung from a hoisting device 22, which may be a block and tackle or a mechanical hoisting equipment. The hook is thrust through the leg in the conventional manner between the bone and the main tendon. The quarter is then lowered into the casing and the open end of the bag is released from the margin of the container 5. As the quarter is raised by the hoisting apparatus, the expanded bag is grasped in such a manner that it rises with the beef quarter and almost completely enshrouds it. After the quarter has been raised to a convenient height, a second hole 12 is driven through the leg with a marlinespike or some similar instrument just behind the inferior tendon. A second hook 14, which is preferably blunted (although a conventional pointed hook may be used if the end is provided with a protective cap), is then pushed against the finger 4 turning it inside out so that it projects into the interior of the bag as shown in Figure 2. The hook 14, now having its hook portion surrounded by the rubber of the finger 4, is thrust through the hole 12 and the hoisting of the quarter continued until the eye of the hook may be engaged with the hook member of the trolley 18. Then, the hoisting apparatus is slackened off and the weight of the quarter is transferred to the hook 14.

The initial hoisting hook 8 is removed and the open mouth of the bag is pulled up and over the shank of the beef quarter, gathered together, twisted, and tied off by two spaced wire ties, as illustrated at 16, Figure 4, or by any other convenient means. An evacuating nozzle is then thrust through the nipple 20 which is formed on the bag and the air between the bag and the

quarter is exhausted which causes the bag to collapse against the quarter and hug it tightly all over. The nipple 26 is then twisted and sealed off by means of a crimped wire or other tie.

- 5 Since, by this process, no seal is attempted against the shank hook, the package remains air-tight and free from any troubles arising from leakage. Furthermore, since the hook portion is entirely surrounded by rubber, it is possible to 10 remove the hooks from the quarter whenever desired and to rehang the quarter on hooks at some later time without danger of tearing the bag or admitting air between the bag and the meat.

I claim:

- 15 1. The process of enclosing heavy cuts of meat in flexible and impervious bags which comprises supporting the cut from above while drawing the bag over the cut, inserting a hook into a pocket in the bag, engaging the hook and pocket with the 20 cut, transferring the weight of the cut to the hook, removing the supporting means, and sealing the bag.

2. The process of enclosing a heavy cut of meat in a flexible and impervious bag and adapting the 25 bagged cut to be handled on suspension conveyor systems, which comprises suspending the cut while placing it inside the bag, engaging the cut with a hook from outside the bag without puncturing the bag, transferring the weight of the cut 30 to the hook, removing the suspending means and hermetically sealing the bag.

3. The process of enclosing a heavy cut of meat in a flexible and impervious bag which comprises suspending the cut while drawing the bag over 35 the cut, engaging the cut with a hook from outside the bag without puncturing the bag, transferring the weight of the cut to the hook, remov-

ing the suspending means and sealing the bag hermetically.

4. The process of enclosing heavy cuts of meat in flexible and impervious bags which comprises suspending the cut while placing it inside the 5 bag, inserting a hook into a pocket in the envelope, engaging the hook and pocket with the cut, transferring the weight of the cut to the hook, removing the suspending means and sealing the bag hermetically.

10 5. A flexible impervious bag, adapted to enclose a cut of meat, having a closed end and a tubular projection adapted and arranged to be inserted into the meat and to form an air-tight socket therein into which a suspending hook may 15 be inserted.

6. A cut of meat enclosed in a flexible air-tight bag having a reentrant portion of the bag inserted in the meat and forming an air-tight socket 20 adapted and arranged to receive a suspending hook for supporting the cut.

7. The process of enclosing heavy cuts of meat in air-tight bags and of adapting the enclosed cut to be handled on suspension conveyor systems which includes providing a closed, tubular 25 projection on the bag adjacent its open end, temporarily suspending the cut, inserting the cut in the bag, pushing the closed end of the projection through an aperture provided in the meat cut, thereby turning the projection inside out and 30 forming an air-tight socket adapted to receive a hook, placing a hook within the socket, transferring the weight of the cut to the hook, removing the temporary suspension, gathering the open end of the bag to enshroud the cut, and sealing the 35 bag hermetically.
